UNITED STATES PATENT OFFICE.

PAUL HENRY WALLER, OF CAMBERWELL, LONDON, ENGLAND.

APPARATUS FOR EXHIBITING NOTICES AND THE LIKE.

1,364,906.

Specification of Letters Patent. Patented Jan. 11, 1921.

Original application filed November 10, 1919, Serial No. 336,973. Divided and this application filed March 19, 1920. Serial No. 367,136.

To all whom it may concern:

Be it known that I, PAUL HENRY WALLER, a citizen of the Republic of France, residing at Camberwell, in the county of London, S. E., England, (whose post-office address is 41 Wilson road, Camberwell, in the county of London, S. E., England,) have invented certain new and useful Improvements in or Relating to Apparatus for Exhibiting Notices and the like; and I do hereby declare the following to be a full, clear, and exact description of the invention, such as will enable others skilled in the art to which it appertains to make and use the same.

This application is a division of the application for Letters Patent filed by me on November 10, 1919, Serial Number 336,973.

This invention relates to apparatus for exhibiting notices and the like of the kind described in my pending patent application Serial No. 336,973 filed November 10th 1919, and has for its object to provide that the fares for traveling from one station to any other station on a route can be readily indicated in vehicles such as tramcars and the like. The word "station" as used herein refers to any stopping place at the end of a section of a route at which a change in fare comes into operation.

According to the invention, an indicator of the type described in the aforesaid patent application is characterized by the station labels having each allotted to them a series of fare notices, indicating means (for example electric lamps), one for each notice, for exhibiting the notices, and a switch operated step-by-step and having its contact-pieces connected each to one or more of said indicating means for selectively exhibiting the fare notices.

Conveniently, in an indicator for use in one direction only from one terminus to another the number of contact pieces in the switch is equal to the number of station labels, the station labels have allotted to them one more fare notice successively for each label counted in the direction of travel, and the number of indicating means connected to each contact-piece differs by one from the number thereof connected to each preceding and following contact-piece.

Other features of the invention are described hereinafter.

One embodiment of the invention and a modification thereof are diagrammatically illustrated by way of example in the accompanying drawing wherein:—

Figure 1 shows one form of fare indicator according to the invention suitable for use in tramcars, motor omnibuses and the like between two termini in both directions of travel, and

Fig. 2 is a diagram of connections of the electrical equipment of the indicator shown in Fig. 1; that part of the equipment which is shown in thin lines is used when traveling in one direction, while the remainder thereof shown in thick lines is used when making the return journey from one terminus to the other.

Fig. 3 is a diagram of connections of a modified form of indicator adapted for use on a circular or ring route having only three stations.

Referring first to Figs. 1 and 2 the indicator provided in a vehicle, for example a tramcar, is arranged for seven stations labeled respectively "T," "U," "V," "W," "X," "Y" and "Z." Each station label has allotted to it a series of fare notices whereof that allotted to the station label "Z" reads 1d, 2d, 3d, 4d, 5d, 6d, and all the other station labels may have similar fare notices, as shown in Fig. 1. In carrying out this invention how-

ever some of the fare notices of some of the station labels may be omitted. For instance, the fare notice of station label "W" may be arranged to read 1d, 2d, 3d. This is because in the example illustrated the fare between any one station and the next is always assumed to be one penny, and consequently the fare from the middle station "W" to any other station cannot exceed 3d, while the fare from one terminus to the other will be 6d. Conveniently the fares are exhibited by being mounted on translucent screens, one or more lamps being provided for illuminating each fare on each notice.

As shown in Fig. 2, six lamps T¹ to T⁶ are provided for exhibiting the fare notices allotted to the station label "T," six lamps U^{1*}, U¹ to U⁶ are similarly provided in connection with the station label "U," six lamps V^{1*}, V¹, V^{2*}, V² to V⁴ are provided in connection with the station label "V," six lamps W^{1*}, W¹, W^{2*}, W², W^{3*}, W³, are provided in connection with the station

label "W," six lamps X^{1*} , X^1 , X^{2*} , X^2 to X^4 are provided in connection with the station label "X," six lamps Y^{1*} , Y^1 to Y^5 are provided in connection with the station label "Y" and six lamps Z^1 to Z^6 are provided in connection with the station label "Z," the numerical indicies of these reference characters designate the fares exhibited by the lamps to which the reference characters are applied.

These lamps are all under the control of a rotatable switch K^1 . This switch is connected to an electric main L^1 , and is arranged to sweep over two series of contact-pieces 1^U , 2^V , 3^W , 4^X , 5^Y , 6^Z , and 1^Y , 2^X , 3^W , 4^Y , 5^Z , 6^t , the one series being used when traveling in one direction, and the other when traveling in the other direction. The indices of the reference numerals attached to these contact-pieces indicate each that station label to which is allotted the first of the said lamps directly connected to the contact pieces. For example, the lamp X^1 which is allotted to the station label "X" is the first lamp directly connected to the contact-piece 4^X . The lamps have one of their terminals connected each to one of the contact-pieces of the switch, and can therefore be connected by the latter to one electric main L^1 , while their other terminals are all connected to another electric main M^1 . Those lamps designated by reference characters having a * attached to a numerical index are all connected to the same series of contact-pieces, and are allotted each to a fare notice to which is also allotted a lamp connected to the other series of contact pieces. It will thus be seen that some of the fare notices can be illuminated by one or other of two lamps according to the direction of travel of the vehicle.

The switch K^1 may be manually or mechanically actuated step-by-step in the same manner as described with reference to the corresponding rotatable switch in above mentioned pending application, and the two switches may be mechanically connected together in such a manner that the switch K^1 is moved forward one step whenever the vehicle passes or is about to pass a station.

Assuming that the vehicle is at the terminus T and is about to travel to station Z, and that the switch K^1 is on the contact-piece 1^U it will then be seen that a circuit is completed from the main L^1 through the switch-arm K^1 , the contact-piece 1^U and back through the main M^1 by way of the lamps U^1 , V^2 , W^3 , X^4 , Y^5 , Z^6 , which are connected in parallel. The fare from the terminus T to each station on the route is thus indicated, the fare to the terminus Z being 6d. On arriving at station U the switch arm K^1 will be moved one step forward to contact-piece 2^V when it will be seen that a group of lamps V^1 , W^2 , X^3 , Y^4 , Z^5 will be lighted, thereby indicating a different set of

fares, and that the fare to the other terminus is now 5d.

When the vehicle is making the return journey and is at station X for example then the switch arm K^1 will be on contact-piece 3^W , and the fares 1d, 2d, 3d, 4d, will be indicated by the lamps W^{1*} , V^{2*} , U^3 , T^4 , at the station labels "W," "V," "U," "T," respectively.

It will be seen that if the indicator is required to be used in one direction only say from station T to station Z, then no station label "T" having fare notices allotted thereto need be provided, and the number of contact-pieces in the switch will be equal to the number of station labels. Further, the station labels will have allotted to them one or more fare notices successively counted in the direction of travel, for example while the station label "U" will have allotted to it only one fare notice showing 1d, the station label "V" will have allotted to it two fare notices showing 1d and 2d. Moreover the number of lamps connected to each contact-piece of the switch in the direction of movement thereof will differ by one from the number of lamps connected to each preceding and following contact-piece. For example, as shown, four lamps are connected to the contact-piece 3^W , while five lamps are connected to the contact-piece 2^V and three lamps are connected to the contact-piece 4^X .

It will be seen that in the indicator shown in Figs. 1 and 2 for use in both directions of travel, the second series of contact-pieces 1^Y to 6^t are connected at their allotted lamps in reversed succession as compared with the connection of the first set of contact-pieces with their allotted lamps.

Referring now to Fig. 3, the contact-pieces 1^T , 1^U , 1^V of the switch K^1 are connected each to a group of three lamps, one allotted to each station label "T," "U" and "V." These groups of lamps can be connected successively across the mains L^1 and M^1 by the switch K^1 as the vehicle travels from station to station around the route. Assuming that the vehicle is traveling from station T via station U to station V and has passed station U, the switch-arm K^1 lying on contact-piece 1^V , then the indicator will show that the fares are as follows:—from station U to V 1d, to station T 2d, and to station U^3 3d, it being assumed that each stage costs 1d.

It will be appreciated that more than one indicator may be controlled by one switch, and that any number of fare notices may be allotted to a station label. Also, it will be appreciated that the fare notices may be exhibited in other ways than by illuminating them if so desired, without departing from the scope of the present invention as defined in the claims.

What I claim as my invention and desire to secure by Letters Patent is:—

1. In an indicating apparatus, a series of station labels adapted to be secured in a car, each station label being marked to indicate a separate stopping station and provided with a series of fare notices, an electric indicating device for exhibiting each fare notice, an electric circuit provided with a series of contact pieces which are selectively connected with the electric indicating devices of the said fare notices, the fare notices of each series being arranged in regular succession, and the electric indicating devices of the series of fare notices being connected in parallel and in a predetermined succession so that different and appropriate fare notices are exhibited simultaneously at all the station labels, and a switch included in the electric circuit and adapted to be placed in engagement with the said contact pieces one after another.
2. In an indicating apparatus, a series of

station labels adapted to be secured in a car, each station label being marked to indicate a separate stopping station and provided with a series of fare notices, an electric indicating device for exhibiting each fare notice, an electric circuit provided with a series of contact pieces which are selectively connected with the electric indicating devices of the said fare notices and adapted for use when the car is traveling in one direction, a second series of contact pieces which are selectively connected with the said indicating devices but in reversed succession as compared with the first said series, and a switch included in the electric circuit and adapted to be placed in engagement with the contact pieces of each series one after another.

In testimony whereof I have affixed my signature, in presence of two witnesses.

PAUL HENRY WALLER.
